METHOD OF MAKING NEON ELECTRIC SIGNS AND NEON SIGNS

Filed Nov. 16, 1927

UNITED STATES PATENT OFFICE

WILLIAM W. PURDOM, OF LOS ANGELES, CALIFORNIA

METHOD OF MAKING NEON ELECTRIC SIGNS AND NEON SIGNS

Application filed November 16, 1927. Serial No. 233,629.

This invention relates to improvements in display signs and the like and more particularly to electrically sensitive color-giving gas contained signs.

5 One of the objects of my invention is to provide a simple, efficient, and inexpensive device of this character.

Another object of my invention is to provide an electrically illuminated sign characterized by the feature of intense luminosity 10 obtained at a minimum expense.

A further object of my invention is to provide a color illuminated sign capable of giving a maximum amount of illumination with 15 a minimum amount of current.

Another object of my invention is to provide a colored sign wherein the letters are individually rendered transparent thru the instrumentality of gas as the source of illumination and of prismatic surfaces as the reflectory medium.

A still further object of my invention is to provide a colored sign where the color is furnished to the characters of the sign thru the instrumentality of an electrically sensitive gas, means being provided for housing said gas in a prismatic glass letter-shaped body in a manner consistent with the formation of a weather-proof, air tight seal.

30 Another object of my invention is to provide interchangeable prismatic characters for making up any desired sign, each equipped with an internal channel holding neon gas or its equivalent, with means for furnishing the 35 gas with electrical current whereby to impart color to the gas.

And another purpose of my invention is to provide a sectional prismatic character, whether letter, design or legend, with complementary grooves, designed, when the sections are united to give shape to a continuous channel shaped to the outline of the same letter, design or legend, and showing to good advantage thru the transparent surface of 45 the prismatic character, so that when neon gas or the like is introduced and sealed in said channel and electrically energized by approved means, said gas becomes colored and makes the entire prismatic character luminous at night or day resplendent in this color.

A still further object of my invention is to provide a simple and inexpensive background for each separate color-illuminated letter, with means for connecting the letter to this background in an insulated manner, 55 and in a manner entirely impervious to atmospheric or climatic changes and influences.

Another object of my invention is to render the color-illuminated sign more durable in construction than as made at the present 60 time, less liable to breakage, cracking, deterioration, repairing, leakage, and separation of its component parts.

With the above and other objects in view my invention consists in the combination, arrangement and details of construction disclosed in the drawings and specifications, and then more particularly pointed out in the appended claims.

In the drawings, which are merely illustrative of my invention and in which similar reference characters designate similar parts throughout the respective views,

Figure 1 is a front elevation of a sign equipped with the parts of my invention, 75

Figure 2 is a vertical elevation of one sign character,

Figure 3 is an elevation of the metal background for the character,

Figure 4 is a vertical sectional elevation of 80 the parts of my invention,

Figure 5 is a perspective view of a rubber gasket ring to be described,

Figure 6 is a cross sectional view of the prismatic sections, 85

Figure 7 is a perspective view of two prismatic sections,

Figure 8 is a front elevation of a character, and,

Figures 9, 10, 11, 12, and 13, are end elevations of various prismatic formations of letters or characters.

In the drawings, 10 indicates the particular letter, device, character or legend to which definite outline is given. Prismatic glass is 95 the material from which this letter is to be formed altho any material imparting the desired transparency to the letter will answer the same purpose. The glass letter 10 is shaped to the outline of this device and is 100

formed with a groove 11 opening out of the adjacent face of the device; this groove or channel will take the same direction as the letter, making the turns that the letter itself does so that it may be shaped in similitude to the configuration of this letter.

A second prismatic section 21 made of transparent material is provided to cooperate with the first prismatic section 10 to complete the outline of the glass character, and it may also, if desired, have a groove or channel of the same size and shape as the other groove 11, so that when the two prismatic sections 10 and 21 are secured together to provide a unit, the two grooves will register and provide a duct of the same shape as the letter. However in Figure 4 the channel is shown to open out of the section 10 only, but this arrangement is optional.

It will be seen that the channel would ordinarily intersect the coinciding faces of the two prismatic sections forming the completed character; as a means of introducing the electrically sensitive color-giving gas such as neon, argon, helium, etc. into the channels, there are provided offset ducts communicating with the main channel 12, and also communicating with integral sleeves or nipples, preferably three in number, designated 14, 15, and 16 which project forwardly from the rear side of the section 10; the cross-ducts 11, 17, 13 serving as by-pass connections from the channel to the sleeves. The back face of the section 10 (altho either section could be thus treated, depending on which has the front display reflected surface) is highly polished, so as to have a mirrored reflectory surface as at 25. The central nipple serves as the filling nipple and when the gas has been introduced into the letter this filling nipple will be stopped up or plugged. The gas filling occurs after the prismatic letter has been completed.

I aim to provide an individual background member, preferably of metal, for each separate letter or character made in accordance with my invention. This takes the form of a rectangular sheet 24 opaque in appearance and character and provided, at the proper spaced apart points with a plurality of openings or holes corresponding in size and number to the sleeves 14, 15, and 16, these holes being designated 14^a, 15^a, and 16^a. There are preferably three such holes and their disposition upon the insulator background member 24 varies in accordance with the shape of the letter or design.

The nipples or sleeves 14, 15, and 16 will project snugly thru the holes 14^a, 15^a, and 16^a of the metal background, which background has its front face silvered to produce a mirror surface which throws its reflectory power thru the front of the glass letter. In this manner the letter is properly set into a frame and given support so that the several

letters may be brought into alinement by securing the background plates by means of fasteners 30 upon a common frame or sign board.

The connecting portions 11, 17 and 13 of the channels may taper from large at the outer face of the letter to small at the inner face thereof, as shown in Figure 4. Electrodes of any approved design and construction as may be best suited for the purpose, are caused to project into the counterbores 19^a of the sleeves, for the purpose of bombarding with high tension current the gas enclosed in the channels. These electrodes are preferably of copper and have glass inserts 20' to minimize oxidation of the inert gases filling the latter. 20 designates the leads extending from the electrodes which are in an electrical circuit as is also a transformer enabling the device to be connected directly to the circuit line of buildings.

The electrodes also function to close up the sleeves, two electrodes being shown preferably closing the endmost sleeves of the letter or design. After the electrodes have been installed and connected in relation to the sleeves rubber rings or gaskets 29 are employed and shrunk around the sleeves so that their front faces overlap and engage the rear face of the background; the natural resiliency of the rubber gaskets serve to prevent displacement of the letter with respect to the background board or member 24.

The central or intermediate sleeve 15 functions as the filler portion for supplying the channels which internally compose the letter sections with the proper illuminating gas. To this end the hose thru which issues the gas under pressure, as from a vacuum pump, is fitted tightly around this neck or sleeve 15, and any desirable and effective electrically sensitive color-giving gas such as neon, argon, helium and similar inert gases, may be forced into the channels; when the proper volume of gas has been let into the channel so as to fill the available dimensions thereof, a glass plug of desirable formation 18, is designed to plug up the sleeve 15, thereby retaining the gas wholly within the channel.

This having been done, it is now important to render the device weather-proof and to hermetically seal the enclosed gas in their channels. The completed letter must, to get the best results in winter as well as in summer, or at other seasons, exclude dirt, cold, heat, moisture and other foreign elements, this being also necessary in order to prevent the cracking, splitting or deterioration of the material of the letter. It is designed to have only the front faces of each letter shine with intense luminosity, as signs are usually above the heads of pedestrians and there is no need for exuding light from the edges of the letters of the sign. To this end I smear a heavy liquid paint consisting mostly of a carbona-

ceous content, upon all the edges of the letter except the front side, seeing that the rear side is rendered impervious to light by overlying the background; in this manner the edges of each letter are rendered not only opaque but impervious to atmospheric conditions, thereby sealing the letter in all places where the gas might leak, or foreign elements enter the sign.

5 When the several letters or characters of the signs are painted with the paint 19^b, the letters are ready for use. When the electrical circuit is closed, the electrons discharged from the electrodes bombard the inert gas in the channels of all the letters, as the latter are or may be connected in series with the circuit. The gases now assume a colored brilliancy, and as the gas assumes the shape of a letter the letter itself shines and adopts 15 the color of the gas; the mirrored surface 25 reflects the color to advantage so that the effect of the letter is to radiate an effulgence of colored light visible at great distances day or night.

25 Various prismatic effects may be obtained upon the exterior surfaces of the prismatic sections as may be adapted to enhance ornamentation and luminosity thru radiation. In Figure 12 is shown the device in the form of 30 plain glass having the polished surface usually found in planes; in Figure 9 the prismatic section is shown ribbed as also in Figure 7; in Figure 13 the prismatic section has facets; in Figure 11 this section is latticed; in Figure 35 13 the section is streaked or porcupined.

Neon signs as now made called for the expert services of a glass blower to shape the delicate tubes for housing the gas. The present invention employs no tubage except the 40 short sleeve or nipple sections needed to connect the electrodes. The painted edges of the letters help to focus towards the front the colored rays, the mirror also contributing towards this result; and also prevents that 45 effluvium of color or overflow of light from one letter to another. The background boards function to individualize the letters or designs and may be unscrewed from the super frame of the sign or design holder for adjustment, or reconnection to the power line. The 50 mixture of glass used in forming the letter bodies should contain a sufficiency of lead to insure a close grain of glass to form the prisms. The letters may have borders extending about or around them on the completed sign board and may be of any script or design.

From the foregoing it will be seen that I 55 have devised an improvement in neon signs or the like. I do not mean to limit myself to the exact details of construction disclosed herein but intend to cover all variations falling within the purview of the appended claims.

What I desire to claim and seek by Letters Patent is:—

1. A sign having individual characters, each character being a prismatic body having a highly polished reflecting surface on one side, and having an internal hermetically sealed channel shaped to the outline of the character and containing an electrically active gas exuding a definite color, and means for charging said body channel with said gas. 70

2. A sign having individual letters, an electrical circuit including a transformer, each letter composed of two prismatic sections hermetically sealed together to exclude atmospheric conditions and influences, each letter having an internal channel shaped to the same outline as the letter and containing a color-giving electrically sensitive gas, and electrodes projecting from said channel and included in said transformer circuit. 80

3. A sign consisting of interchangeable letters each composed of prismatic sections, a metallic background to which said letters are individually attached, the surface of each letter engaging the background having a 90 polished reflectory surface, an electrical circuit including a transformer, each letter having an internal channel shaped to the configuration of the letter and containing neon gas or the like, electrodes plugging outlets 95 from said channels and connected to said electrical circuit, and a cementitious substance lining the exposed surfaces of the individual respective letters except the front side thereof. 100

4. A sign composed of glass letters having mirror surfaces at their rear portions, a source of colored light following the direction of the letter, and electrical means for wholly retaining the source of colored light within the letters. 105

5. A sign composed of transparent characters, means rendering each letter opaque upon all but its front and lateral surfaces, a mirror surface on the rear side of each letter, a source of colored illumination in 110 each character and shaped to the outline of this character, a support for all the letters forming also a background for the letters, and means for removing the source of colored illumination from said letters individually. 115

6. In combination a frame, a plurality of interchangeable letters removably secured to said frame, each letter having a transparent front surface and having an internal channel shaped to the same configuration as the letter 120 and containing neon gas, an electrical circuit including a transformer, means for connecting all letters in series to said circuit, means for introducing the gas into the several letters, and painted linings on all sides of each letter except the front and rear. 125

7. In combination a frame, a plurality of glass letters each sectionally held together and providing complementarily an internal channel shaped to the outline of said letter, 130

a plurality of integral sleeves carried by each letter at its rear and projecting thru the frame, electrodes closing some of said sleeves, means establishing communication between each channel and the sleeves of the letter, an 5 electrically sensitive and color-emitting gas contained in said channel and introduced thru other sleeves, plugs closing the last-mentioned sleeves, and means for electrically energizing all the letters thru the medium 10 of said gas.

8. A prismatic letter composed of two mating sections having flat surfaces designed to be cemented transparently together with a hermetically tight joint, either or both sections providing an internal channel for the passage therethru and retention of neon gas, means formed integrally upon the rear side of the letter providing inlets for said gas, 15 means connecting the channel in an electrical circuit.

9. A prismatic letter composed of two mating sections cemented together into a single unit, said sections bored out to produce 20 an internal channel shaped to the outline of the letter, neon gas contained in said channel, and means sealing said gas in said channel against escape.

10. A prismatic letter composed of two sections cemented together to form a unit, 30 said sections providing an internal bore shaped to the outline of the letter itself, an electrically sensitive color-giving gas housed in said channel for rendering the same luminous, the rear face of the letter having a reflective surface, the edges of the letter being rendered opaque, leaving the front side transparent to display the color of the internal channel, under the reflection of said reflective surface.

40 11. In combination a metal background having several holes, a glass letter having on its rear surface three sleeves projecting thru the holes of the background to juxtapose the letter in overlapping relation to the background, the glass letter having an internal gas-filled channel shaped to the outline of the letter and communicating with all of said sleeves, one of said sleeves serving as the inlet 45 for introducing the gas into the letter, and electrodes plugging the other sleeves and having ducts for transmitting electrical energy to said gas to render the latter color-giving.

50 12. In combination a metal background having three holes, a two-section prismatic glass letter having upon its rear side several sleeves projecting thru said holes, the metal background member overlying the rear side of the letter, the surface of the letter engaging said background being mirrored, rubber gaskets embracing said sleeves and binding against the rear sides of said background to position said glass letter in proper registration with said background, said letter having 55 an internal channel shaped to the outline

of the letter and containing neon gas, electrodes transmitting electrical energy to said gas and also sealing the end sleeves of the letter, and a closure means for stopping up the central sleeve thru the latter of which the 70 neon gas is introduced into the letter.

13. A metal sheet having a plurality of holes, an all-glass letter having an internal channel shaped similarly to said letter and being itself letter-inclined, integral nipples formed so as to project outwardly from the rear of said glass letter, and projecting thru the holes of said background, means preventing the displacement of said letter from said background and also providing an air-tight 75 seal thereabout, said channel communicating with said sleeves, electrical means projecting into said sleeves for energizing gas contained in said channel, a glass plug closing one of said sleeves, and means providing a hermetic seal between said electrodes, glass plug and the sleeves controlled thereby.

In witness whereof he has hereunder set his hand this eleventh day of November, 1927.

WILLIAM W. PURDOM.
